UNITED STATES PATENT OFFICE.

ROBERT C. CHILD, OF BROOKLINE, MASSACHUSETTS, ASSIGNOR TO G. E. PRENTICE MANUFACTURING COMPANY, OF NEW BRITAIN, CONNECTICUT, A CORPORATION OF CONNECTICUT.

BAG, POCKET, OR POUCH, AND CLOSURE THEREFOR.

Application filed July 25, 1928. Serial No. 295,288.

This invention is in containers such as bags, pockets or pouches. One useful embodiment of the invention comprises a portable pouch, which may, for example, be of dimensions 5 adapting it to be carried in a clothing pocket, to serve to contain anything requiring to be enclosed; typically such supplies as smoking tobacco, or a pipe, or both tobacco and a pipe.

Objects of the invention are to provide an 10 article of this nature having a closure so that when open, the mouth opening provides at least as much free space for access to the interior as is provided by the interior dimensions of the pouch, the closure being such as 15 effectively to retain small or granular contents. Another object of the invention is to provide a durable and convenient tobacco pouch having a mouth opening of such width and flexibility as to admit the bowl of a pipe, 20 and the hand of the user, if desired, and having a closure device nevertheless capable of holding the opening closed and guarding against spilling the contents. Another object of the invention is to provide a pouch 25 closure of a type adapted to be fastened by any of the kinds of slider-actuated interlocking multiple-engaging-element types of fastener in closed position, which when open, will permit the engaging elements to be wide- 30 ly separated.

Referring now to the accompanying drawings, which illustrate a preferred form of the invention for purposes of explanation only, and which are not to be understood as showing the only embodiment of the invention,

Fig. 1 is a perspective view of a pouch in open condition;

Fig. 2 is a similar view of the pouch in closed condition; and

Fig. 3 is an elevation of a blank of material used to form a part of the closure.

The pouch may be principally comprised of any bag of light, strong, and flexible material, for example, made up of two like blanks 45 1, 1, of suitable material, such as leather, imitation leather, cloth, any flexible fabric such as rubber, rubberized or oiled silk, cotton or other textile fabric, or any fabric treated with coating material suitable to the uses of such 50 a bag or pouch. The blanks 1, 1, may be of any desired form, preferably having rounded contours at least at the corners 2, 2, and these blanks may be overlaid one on the other and conjoined together except at certain margin-

nal edges for the opening in any desirable 55 way; for example by a sewed seam 3. But the pouch may be made of an integral piece of fabric, if desired, turned up into a side seamed bag having an open mouth and one expansible or open side, with the same effect 60 as the two-blank seamed pouch shown.

In manufacturing the article the seam 3 is not completed to form a side seam at one of the side edges of the overlaid blanks 1, 1, but is left open from the point 4 or thereabouts 65 of one side of the pocket or pouch to be formed, for example, the side 5. The parts of the side edges at 5 of the pouch are free to be separated from each other, so that the corners 6, 6, of the blanks 1 may be separated so far 70 as desired, to provide, with the adjacent mouth edges, a wide mouth triangular in general shape, as best illustrated in Fig. 1, for free access to the interior of the pouch. The corner 7 of the mouth of the finished article 75 may be conjoined by stitches of the seam 3 or parts of fastening means, such as a metal staple or stop 8 for a slider 10 having the usual wedge or plough element and directing channels of any of the well-known types 80 of slider-actuated mutually interlocking engaging elements of such fastening devices.

The mouth edges of the pouch may be finished from end to end by attachment to these edges in any desired way of stringer 85 members 12, 12, (usually tapes or other selvaged woven strips) bearing on their free edges respectively the engaging elements 14 worked by the slide 10.

While any mode of attaching the engaging 90 elements 14 directly to, or of attaching stringers 12 to the upper open edges of the blanks 1, 1, may be resorted to, as shown and preferred the strips 12 are conjoined to the blanks 1 by sewed seams 15, 15, which extend from 95 end to end of one edge of each of the blanks 1. In making these articles, it will be understood that a continuous length of the stringers 12, before or after the attachment of elements 14 may be sewed to a succession of blanks 1 as a 100 continuous operation, the pouches being cut apart by severing the strips 12 at the edges of the blanks 1 before or after their assembly by making the seams 3.

The pouch is completed by providing an 105 extensible and collapsible stop 16 closing against spilling the contents, the open side seam adjacent to the mouth edges provided

with the series of fastener elements 14. Stop 16 may be made as a bellows-folded piece, of the same material as or a more flexible material than the blanks 1, 1, the edges only of stop 16 being securely attached to the side seam opening from 4 to 6 left in the pouch when the side seam 3 is sewed. As best shown in Fig. 3, a preferred form of the stop 16 comprises a generally triangular blank set or creased inwardly along the lines 18 to provide radial bellows folds, and creased outwardly along the line 19 to provide an outward bellows fold. The stop 16 may be attached along its edge a to one of the blanks 1 by a seam 3^b before sewing the seam 3, which may be continued at 3^a in respect to the other edge of the stop 16 and the other blank 1 only. Preferably the contour of the top edge of the blank 16 is relatively concave, as shown at 20, (Fig. 3) to avoid contact with the slider 10 when the slider is operated to close the pouch. When the pouch is closed by slider 10 the corners 6 are held together with the folded stop 16 compressed between them, and within the closed pouch.

It will be observed that any interior pressure of contents will merely hold the top edge 20 of the folded stop 16 against the fastener edge; but when the slider is moved to open the pouch, the stop 16 forms a cross wall of a triangular mouth, between its edge and the edges carrying the fastener elements. A place for the insertion of the thumb or finger of the user to grasp the corners 6 or the edges 5 near the corners 6 and to open the pouch merely by separating the corners 6 is provided by the slight separation of the main blanks 1, 1, by the folded or collapsed stop 16, and on such separation the slider 10 reacts to move to the open position shown in Fig. 2.

To prevent the slider 10 from passing off the engaging elements 14, an abutment stop 20^a is applied to one (or a stop 20^a to each) of the mouth edges of the pouch. The stop 20^a does not connect these mouth edges, so that the corners 6 are free to separate.

I claim:

1. Pouch having a mouth comprising edges free to separate at one only of the corners of the mouth, an expansible and collapsible stop conjoined severally to adjacent edges of the pouch at said corner, and slider-actuated fastening means having engageable elements respectively on the separable edges. 50 55

2. Pouch having a normally open mouth and having one side provided with an extensible and collapsible inserted stop, the edges of the mouth being provided with engageable fastener elements adapted to be actuated by a slider, and a slider adapted to move said engageable elements into engagement and to hold said stop in collapsed relation at one extreme of its motion. 60

3. Pouch having side and mouth edges of its material at an angle to each other, the mouth edges being provided with engageable elements of a slider actuated fastener adapted in closed position to hold the ends of the side edges closely together, and having a collapsible stop bridging and between said side edges and adapted to be held in collapsed relation between said side edges when the slider is in closed position. 65 70

4. Pouch having a mouth comprising edges free to separate at one only of the corners of the mouth, an expansible and collapsible stop conjoined severally to adjacent edges of the pouch at said corner, and slider-actuated fastening means having engageable elements respectively on the separable edges, one of the edges at the separable corner of the mouth being provided with an abutment stop preventing motion of the slider off the fastener means at that corner. 75 80 85

5. An article having a gap therein, means permanently uniting the edges of the gap at one end, extensible means connecting the opposite edges of the gap at its other end, series of fastener elements at the opposite edges respectively of the gap, and a slider for moving the fastener elements of the opposed series into gap closing relationship. 90

Signed by me at Boston, Massachusetts, this 20th day of July, 1928.
